Primary Examiner — Karen S Acker*Assistant Examiner* — Wendy Arminio*(74) Attorney, Agent, or Firm* — Dascenzo Intellectual Property Law, P.C.(57) **CLAIM**

The ornamental design for a pet food container, as shown and described.

DESCRIPTION

FIG. 1 is an isometric view of a pet food container with the new design;

FIG. 2 is another isometric view thereof;

FIG. 3 is a bottom view thereof;

FIG. 4 is a side view thereof;

FIG. 5 is another side view thereof;

FIG. 6 is another side view thereof; and,

FIG. 7 is another side view thereof.

The broken lines and the outer edge of the rim of the pet food container illustrate features of the article that form no part of the claimed design. The broken line rectangle and broken lines within it are portions of the pet food container that are not included in the claim.
